UNITED STATES PATENT OFFICE

FREDRIK LJUNGSTRÖM, OF LIDINGÖ-BREVIK, AND ALF LYSHOLM, OF STOCKHOLM, SWEDEN, ASSIGNEES TO AKTIEBOLAGET LJUNGSTRÖMS ÅNGTURBIN, OF STOCKHOLM, SWEDEN, A CORPORATION

CONDENSER PLANT FOR LOCOMOTIVES AND SIMILAR VEHICLES

Original application filed August 17, 1922, Serial No. 582,561, and in Sweden March 16, 1922. Divided and this application filed December 17, 1926. Serial No. 155,497.

The present invention refers to locomotives and similar vehicles. The object of the invention is to provide in a vehicle of the kind described a condenser plant of a high efficiency for the exhaust steam of the main machinery of the locomotive or the like, such condenser plant also including a re-cooling device for the cooling liquid of the condenser.

In the accompanying drawings two embodiments of the invention are illustrated. Figs. 1 and 2 are a sectional side view and a cross section respectively of the first embodiment of a condenser plant in a locomotive according to the invention and Figs. 3 and 4 are similar views of the second embodiment.

The condenser plant shown in the drawings is placed on a separate carriage which is supposed to be coupled with a carriage running in front of its left end and supporting the steam boiler of the locomotive and, if desired, other aggregates pertaining to the latter. The arrow 10 designates the normal running direction of the locomotive. The main machinery of the locomotive is shown to consist of a steam turbine 11 disposed on the same carriage as the condenser plant, the power from said turbine 11 being transmitted to the wheels by means of a toothed gearing 12.

In Figs. 1 and 2, 14 is a receptacle, filled with water or other cooling liquid to level 18. Below level 18 a number of tubes or pipes 13 extend through the receptacle 14 from a steam chamber *a* to a chamber *b*. The receptacle 14 forms part of a re-cooling device, which also includes an air-cooled part consisting of closed elements 15 and 16 placed at the side of one another, a plurality of fans 17 being provided for moving the air through the air-cooled part. The fans are situated above the receptacle at the side of one another.

Steam is led from the turbine 11 through the tubes or pipes 13 located within the receptacle 14 and surrounded by the water in the receptacle 14, said water consequently cooling directly the steam as in a surface condenser.

The air-cooled part 15, 16 is connected by means of the ascending pipe 19 with the receptacle 14 above its water level 18. The re-

cooling of the water contained in the receptacle 14 is effected by the water heated therein being pumped by means of a pump 21 through the pipes 19 and the distributing pipe 20 to the cooling elements 15, 16 from which heat is delivered to the air that is being forced between said elements. When the water has been cooled it flows back to the receptacle 14 through pipes 28 and 29 and is caused to rain down into the lower part of the receptacle from a perforated diaphragm 22, as shown in Fig. 2. This diaphragm has for its purpose to distribute the cooled water more evenly as small drops over the water surface in the receptacle thus effecting a good mixing of the cooled water with the warmer water contained in said receptacle.

The fans 17 are driven by means of a driving aggregate, which preferably consists of a steam turbine 23, a toothed gearing 23^a, a transmitting shaft 23^b and bevelled gearings 23^c. The same driving aggregate also serves for driving the pump 21 by means of a transmitting shaft 23^d extending from one of said bevelled gearings 23. To condense the exhaust steam of the turbine 23 there is provided a separate jet condenser 24 receiving its water from the distributing pipe 20 by means of a pipe 24^a. The receptacle 14 as well as the surface condenser 13 are preferably provided with air outlets 25 and 26, and the surface condenser is, as at 27, connected to a condensate pump in usual manner. The condensate is returned to the steam boiler by means of the feed pump.

The embodiment shown in Figs. 3 and 4 differs from that shown in Figs. 1 and 2 by the waste steam from the turbine 11 passing around tubes or pipes 30 through which cooling water is conducted. Re-cooling is effected by the water being pumped through the re-cooling device by a pump, which is omitted in the drawing but may be similar to the one shown in Fig. 1. The driving aggregate 31 of the fans 17 consists also in this case of a steam turbine, the waste steam of which is conducted in the direction of the arrow 32 to the same surface condenser that cools the waste steam of the main turbine 11.

What we claim as new and desire to secure by Letters Patent of the United States is:—

1. In locomotives and similar vehicles, an accumulating receptacle containing cooling liquid, a plurality of pipes arranged within said receptacle below the surface of said cooling liquid, said pipes being adapted to work as a surface condenser, means for bringing the exhaust steam of the main machinery of the locomotive into contact with said pipes in order to condense said steam, an air-cooled part consisting of closed elements, means for circulating cooling liquid from said receptacle through said air-cooled part and a fan for moving the air necessary for cooling through said air-cooled part.
2. In locomotives and similar vehicles, an accumulating receptacle containing cooling liquid, a plurality of pipes arranged within said receptacle below the surface of said cooling liquid, said pipes being adapted to work as a surface condenser, means for bringing the exhaust steam of the main machinery of the locomotive into contact with said pipes in order to condense said steam, an air-cooled part consisting of closed elements, a pump for circulating cooling liquid from said receptacle through said air-cooled part and a plurality of fans situated above said receptacle at the side of one another for moving air through said air-cooled part.

In testimony whereof we have hereunto affixed our signatures.

FREDRIK LJUNGSTRÖM.
ALF LYSHOLM.
